UNITED STATES PATENT OFFICE

2,470,196

ELECTRICAL CONNECTOR

William Henry Thrasher, Birmingham, Ala.

Application November 28, 1947, Serial No. 788,543

1 Claim. (Cl. 173—361)

1

The present invention relates to electrical connectors and it consists in the combinations, constructions and arrangements of parts herein described and claimed.

It is an object of the invention to provide an electrical connector which is simple and economical in its construction and effective in use.

Another object of the invention is the provision of novel means for mounting an electrical connector upon an electrical device with which it is to be used.

Another object of the invention is to provide an electrical connector having a novel combined body and bracket therefor.

Other and further objects of the invention will become apparent from a reading of the following specification taken in conjunction with the drawings, in which:

Figure 1 is a plan view of an embodiment of the invention,

Figure 2 is a side elevational view of Figure 1,

Figure 3 is a sectional view taken along line 3—3 of Figure 2,

Figure 4 is an end elevational view of the device shown in Figures 1 and 2, and

Figure 5 is a sectional view taken along line 5—5 of Figure 2.

Generally, the invention comprises an electrical connector which may be easily and simply attached to an electrical appliance such as, for example, an electrical "hot plate" or the like. It comprises a body formed of a single piece of metal bent into a U-shape and having one of the arms of the body thus formed continue in a vertical direction to form one side of a clamp or bracket. Another side of the clamp is interconnected therewith by means of a bolt and a thumbscrew is provided for the bolt. A socket member is welded to the inner sides of the outer ends of the arms of the body and the base of the body has mounted therein a pair of suitably insulated prongs which extend inwardly of the body toward the socket member.

Referring now more particularly to the drawings, there is shown therein an electrical connector having a U-shaped body 10 comprising an upper arm 11, a base 12 and a lower arm 13. The outer end of the arm 11 extends vertically to form a clamp member 14 through the upper end of which extends a bolt 15 having an enlarged head 16. A thumbscrew 17 is provided for the bolt 15.

A socket member 18 is formed of a single piece of flat material bent substantially into an oval shape and is beveled, as indicated at 19 and thereafter inserted between the outer ends of the arms 11 and 13 and welded thereto.

A pair of electrical connectors or prongs 20 ex-

2

tend inwardly through the base 12 to positions within the socket member 18. Insulating members 21, formed of rubber or the like, are adapted to surround the prongs 20 adjacent the base 12.

5 A block of asbestos 22 is placed within the body 10 adjacent the base 12 and a like block 23 is placed against the outer side of the base 12. Lock nuts 24 are threaded upon the prongs 20 within the body 10 and each of the prongs 20 is provided with a pair of lock nuts 25 on its outer end between each of which pair of nuts 25 is mounted an electrical lead wire 26.

In operation, it will be seen that the device is of extremely simple yet rigid construction and that after it is assembled it is merely necessary to clamp the device to an electrical appliance by means of the bolt 15 with its enlarged head 16 and the clamping arm 14 and thumbscrew 17 and that thereafter the leads 26 may be connected in the conventional manner whereupon a female electrical connector may be inserted within the socket 18 and the prongs 20 will make contact with said female member. The flanged portion 19 will act as a guide for the insertion of the female member.

15 20 While but one form of the invention has been shown and described herein, it will be readily apparent to those skilled in the art that many minor modifications may be made without departing 25 from the spirit of the invention or the scope of the appended claim.

What is claimed is:

25 A device of the character described comprising a U-shaped body member, a socket member affixed between the arms thereof, a pair of contact members extending through the base of the body member to the socket member, insulation between the contact members, a clamping arm formed integrally with the body and extending 40 at a right angle therefrom and fastening means carried at the outer end of said clamping arm.

WILLIAM HENRY THRASHER.
